W. BARRATT,
ATMOSPHERIC GAS BURNER.
APPLICATION FILED APR. 2, 1919.

1,308,472.

Patented July 1, 1919.

FIG. 1.

FIG. 3.

FIG. 2.

Inventor:
William Barratt.
By: B. Anger
Atty.

UNITED STATES PATENT OFFICE.

WILLIAM BARRATT, OF COBURG, VICTORIA, AUSTRALIA.

ATMOSPHERIC GAS-BURNER.

1,308,472.

Specification of Letters Patent. Patented July 1, 1919.

Application filed April 2, 1919. Serial No. 287,049.

To all whom it may concern:

Be it known that I, WILLIAM BARRATT, a subject of the King of Great Britain, residing at 149 Barrow street, Coburg, in the State of Victoria, Commonwealth of Australia, mechanic, have invented certain new and useful Improvements in Atmospheric Gas-Burners, of which the following is a specification.

- 10 This invention relates to improvements in atmospheric gas burners and it is directed more particularly to gas burners of that type which is employed to heat small furnaces, bath heaters and the like.
- 15 The object of the present invention is to provide a burner wherein a thorough admixture of gas and air will be effected in a proper proportion to insure the complete combustion of the gas directly it escapes 20 from the burner and thereby produce a maximum of heat from the amount of gas consumed.

The invention briefly consists in providing a mixing chamber wherein is located 25 an axially disposed gas jet which is connected to a supply pipe and in arranging a number of holes in the periphery of the said chamber for the admission of air. The forward end of the mixing chamber in line with 30 the gas jet is provided with a nozzle and fitting around the same and extending therebeyond is a larger nozzle having separate air inlets. Means are provided for regulating the admission of air to the burner 35 to enable a properly proportioned mixture to be effected from a given pressure of gas.

Referring now to drawings:

Figure 1, is a view in sectional side elevation of a burner constructed in accordance with the present invention, and

Figs. 2, and 3, are views in sectional end elevation taken on the dotted lines 2—2 and 3—3, respectively, of Fig. 1.

The burner comprises a mixing chamber 45 *a* of cylindrical or other approved formation having a hole *b* located centrally in one end and the other end provided with a tapered nozzle *c*. A gas jet *d* is screwed or otherwise rigidly fitted into the hole *b* 50 in the outer end of the mixing chamber and the said gas jet, preferably is formed with a tapered bore *e* as shown by the dotted lines in Fig. 1 of the drawings.

The gas jet *d* is connected to a gas supply 55 pipe (not shown) in any approved way and this pipe can be provided with a cock (not

shown) or like device for regulating the quantity of gas passing therethrough.

A number of air admission holes *f* are formed in the periphery of the mixing 60 chamber *a* and means such as a sleeve valve *g* furnished with holes *h* is fitted rotatably over the said chamber. If preferred the sleeve valve *g* can be fitted slidably over the mixing chamber instead of rotatably as 65 shown in the drawings. The holes *f* in the walls of the mixing chamber and the holes *h* in the sleeve valve *g* correspond in size and shape and are so arranged that the sleeve valve can be adjusted by partially 70 rotating the same to regulate the admission of air to the mixing chamber.

A nozzle *i* is fitted concentrically around the nozzle *c* on the end of the mixing chamber and the annular space *j* between the two 75 nozzles is sufficiently large to permit of a free draft of air therethrough. The outer nozzle *i* is of greater length than and extends beyond the nozzle *c* on the mixing chamber and means may be provided for 80 regulating the admission of air to the rear end of the outer nozzle.

The outer nozzle *i* can be formed integrally with the inner nozzle *c* and supported thereon by radial arms or spiders 85 *v* as shown in Fig. 2, of the drawings.

The nozzles *c* and *i* can be of any desired length and shape to insure a required draft and the air inlets to the mixing chamber and to the nozzles can be adjusted to insure 90 the correct amount of air to be admitted at the different points to effect a properly proportioned mixture and consequently the generation of a very hot flame when the said mixture is ignited at the end of the 95 outer nozzle.

When the mixture is ignited at the end of the outer nozzle *i* the heat of the flame induces a draft therethrough or "pull" on the air at the outer end thereof thereby 100 causing air to be drawn into the said nozzle in correct quantities to produce a properly proportioned mixture of gas and air to effect complete combustion and the generation of a maximum amount of heat.

A gas burner constructed as hereinbefore described will be inexpensive to manufacture and will be found highly efficient by metal workers such as silversmiths and goldsmiths for melting metal in crucibles 105 and the like as it is equally as or more effective and requires less attention than those.

gas burners commonly used and requiring a forced air blast.

I claim:

- The herein described burner comprising
- 5 a hollow member forming a mixing chamber, provided in its side wall with air inlet openings and at one end with an opening for the reception of a gas jet; a nozzle detachably connected to the opposite end of
  - 10 the said member and projecting therefrom, an outer nozzle open at its inner end and in which the first named nozzle is arranged, said outer nozzle being directly permanently connected to and carried by the first named

nozzle and detachable therewith from said 15 member, and the open rear end of said outer nozzle forming an air intake independently of the mixing chamber, and regulating means to vary the effective area of the air inlet opening of the said first named member. 20

In testimony whereof I have affixed my signature in the presence of two witnesses.

WILLIAM BARRATT.

Witnesses:

ALFRED GURR,
HARRY N. MATTERS.
